ATTORNEY

UNITED STATES PATENT OFFICE

ALFRED M. THOMSEN, OF SAN FRANCISCO, CALIFORNIA

ROTARY ORE FURNACE

Application filed June 24, 1929. Serial No. 373,252.

This invention relates to ore furnaces of the rotary type; and it consists in the novel construction, combination, and arrangement of parts hereinafter described, and later claimed.

The object of my invention is to provide, at a low manufacturing cost, a practical and efficient furnace of the rotary type for the roasting of ores, suitable for continuous operation as distinguished from batch operation, and in which the roasting period for the ores may be regulated and controlled. My furnace is especially adapted for roasting ores requiring volatilization.

15 In order that my invention may be clearly understood and readily carried into effect, the same is hereinafter described with reference to the accompanying drawings, in which similar numerals indicate like parts. Of such

20 drawings,

Fig. 1 is a longitudinal section of my device.

Fig. 2 is a cross-section through the line "A—B", Fig. 1.

25 Fig. 3 is a cross-section through the line "C—D", Fig. 1.

In detail, my construction consists of a horizontally disposed cylindrical metal shell, 2, provided with front and rear heads, 3 and 4, respectively, each provided with circular openings, 5. The inner surfaces of the shell and the heads are faced with protective material. Collars, 6, also of protective material, are provided for said openings, 5. Suitably

30 attached to the outer surface of said shell are tires, 7, adapted to roll on flanged trunnions, 8, keyed on parallel horizontally disposed driven shafts, 9, rotatable within journals, 10, mounted on suitable supports, 11. By placing

40 the trunnions with their flanged portions adjacent to the heads any tendency for the shell to move laterally is checked. Any suitable means may be employed to drive the driven shafts, 9. The horizontal disposition 45 of the shell avoids the necessity of gearing, eliminates all need for thrust bearings, and requires utilization of the minimum of power for rotating the shell.

From a suitable supply source (not shown) 50 ore to be roasted is admitted into the shell

through a feed-pipe, 12, inserted through the rear head, 4, and terminating within the shell. The front head, 3, is provided with a vent, 13, through which the calcined material is discharged. The amount of calcined material discharged with each revolution of the shell is controlled by a gate, 14. Heat for calcining purposes, emanating from a suitable fire-box, 15, is admitted into the shell through the opening, 5, in the front head, 3, 55 and the gases produced by the roasting of the ores, together with the products of combustion, are carried off through the opening, 5, in the rear head, 4, into the flue, 16, for whatever further treatment they may require.

60 My device is operated as follows: Power is applied and the shell caused to rotate. Ore to be roasted is then fed into the shell in a continuous stream by means of the feed-pipe. The ore thus fed tends constantly to seek a level within the shell, due to the rotary motion of the shell itself and also to the pressure exerted by the mass of incoming ore. But as the shell rotates the roasted ore is intermittently discharged from the shell 65 through the vent located in the front head which travels in a circular path concentric with the axis of the shell.

70 The size of the vent determines the amount of ore discharged at each revolution of the shell, and, consequently, how long the ore remains within the shell. I control the size of the vent by means of the gate, and am thus able to regulate the duration of the roasting process in a continuous feed rotary furnace.

75 I claim:

1. A continuous feed ore furnace, consisting of a horizontally disposed cylindrical shell rotatable about a horizontal axis; heads for said shell located at opposite ends thereof; tires for said shell supported on rotatable trunnions carried by parallel shafts; checks for said trunnions adapted to engage said tires; an ore intake and a heat intake oppositely located in said opposing heads; an open passage for the intermittent direct discharge of calcined ore suitably located in said heat intake head; and an adjustably mounted gate for said passage.

80 2. A continuous feed ore furnace, consist-

- ing of a horizontally disposed cylindrical shell rotatable about a horizontal axis; opposing heads for said shell, one provided with a heat intake, the other with an untreated ore intake; tires for said shell supported on rotatable trunnions carried by parallel shafts; checks for said trunnions adapted to engage said tires; an open passage-way for the direct discharge of calcined ore located 5 in said heat intake head; and means for regulating the roasting period for the ore, the same consisting of an adjustably mounted door for said passage-way.
3. A continuous feed ore furnace, consisting of a horizontally disposed cylindrical shell rotatable about a horizontal axis; opposing heads for said shell, one provided with a heat intake, the other with an untreated ore intake; an open passage-way in 10 said heat intake head whereby calcined ore is intermittently discharged direct from said shell when said shell is being rotated; and an adjustably mounted gate for said passage-way.
4. A continuous feed ore furnace, consisting of a horizontally disposed cylindrical shell rotatable about a horizontal axis; opposing heads for said shell, one provided with a heat intake, the other with an untreated ore 15 intake; rotatable trunnions for said shell; checks for said trunnions; and means for controlling the duration of the roasting period, the same consisting of an open passage-way for calcined ores located in said heat intake head, and an adjustably mounted door for said passage-way.
5. A continuous feed ore furnace, consisting of a horizontally disposed cylindrical shell rotatable about a horizontal axis; opposing heads for said shell, one provided with a heat intake, the other with an untreated ore intake; and an open passage-way provided with an adjustably mounted gate located in said heat intake head for regulating 20 the duration of the ore roasting period.
6. A continuous feed ore furnace, consisting of a horizontally disposed cylindrical shell rotatable about a horizontal axis; opposing heads for said shell, one provided with a heat intake, the other with an untreated ore intake; and an open regulatory passageway 25 for calcined ores and for the admission of secondary air located in said heat intake head and provided with an adjustably mounted gate.
7. A continuous feed ore furnace, consisting of a horizontally disposed cylindrical shell rotatable about a horizontal axis; a heat intake head and an untreated ore intake head located at opposite ends of said shell; an open passage-way located in said heat intake head, by means of which secondary air is admitted 30 to ores being calcined and calcined ores are intermittently discharged direct from the shell while the latter is being rotated, and an 35
- adjustably mounted gate for said passage-way.
8. A continuous feed ore furnace, consisting of a horizontally disposed cylindrical shell rotatable about a horizontal axis; opposing heads for said shell, one provided with a heat intake, the other with an untreated ore intake; and means whereby calcined ores 40 may be intermittently discharged direct from said shell during the roasting period, the same consisting of an open passage-way located in said heat intake head and provided with an adjustably mounted door.
- In testimony whereof, I hereunto set my signature.
- ALFRED M. THOMSEN.
